UNITED STATES PATENT OFFICE.

LUDWIG W. ZAAR AND JOSEPH UEBELAKER, OF CHICAGO, ILLINOIS.

BOX-TIE.

1,117,298.

Specification of Letters Patent.

Patented Nov. 17, 1914.

Application filed April 9, 1914. Serial No. 830,620.

To all whom it may concern:

Be it known that we, LUDWIG W. ZAAR and JOSEPH UEBELAKER, former subjects of the Emperor of Austria-Hungary, who have 5 declared our intention of becoming citizens of the United States, and residents of the city of Chicago, county of Cook, and State of Illinois, have invented certain new and useful Improvements in Box-Ties, of which 10 the following is a specification.

Our invention relates to ties for boxes, and more particularly to ties for paper boxes.

The object of this improvement is to 15 provide a simple and effective means for tying up a paper box and providing a handle therefor.

A further object is to provide stiffening 20 means for reinforcing the sides of the box.

Other objects will appear hereinafter.

With these objects in view, the invention consists in the combinations and arrangements of parts hereinafter described and claimed.

The invention will be best understood by 25 reference to the accompanying drawing forming a part of this specification, and in which,

Figure 1 is a view, in perspective, of a 30 box equipped with a tie embodying our invention, and Fig. 2 is an enlarged section of the same taken near the central portion of the box.

The preferred form of construction, as 35 illustrated in the accompanying drawing, comprises a paper box 3 of the "set-up" type, but may be of any form of foldable box having a removable lid. A lid 4 provided with flanges 5 is fitted on the box 40 3 in the usual manner.

Our invention consists in providing a tie 45 for a box of the character mentioned and may be applied to any size or shape of such box. The tie consists of cords 6 and 7. The ends of each of said cords are passed 50 through suitable openings in the sides of box 3 and a suitable washer 8 on the inner wall of the box. At the inner side of washers 8 the cords 6 and 7 are knotted or otherwise enlarged to prevent the ends thereof

from passing through said washers. The cords 6 and 7 are of such lengths that when secured to the box 3 they may be passed over the corners 9 of the lid to a position such as indicated by dotted lines 6' and 7' 55 in Fig. 1. When in this position the lid 4 may be removed in the ordinary manner.

The cords 6 and 7 when placed in the positions indicated by full lines in the drawing are adapted to hold the lid from vertical 60 movement on box 3 and are held in said positions by means of the handle member 10. The handle member is provided with hooks 11 at its ends adapted to engage the cords 6 and 7 and the latter may be unhooked or freed therefrom in order to move them to their dotted line positions for opening the box.

The construction set forth provides a 65 box tie which not only binds the lid to the box but by means of the ends of the tie passing around the flange 5 of the lid and into box 3, the top edges of the box are bound firmly against the inner side of the flange 5. This provides a means for stiffening 70 the box walls so that the box is strengthened and eliminates to a great degree, damaging goods contained in the box through rough handling.

While we have illustrated and described 75 the preferred form of construction for carrying our invention into effect, this is capable of variation and modification without departing from the spirit of the invention. We, therefore, do not wish to be limited to 80 the precise details of construction set forth, but desire to avail ourselves of such variations and modifications as come within the scope of the appended claim.

Having described our invention what 85 we claim as new and desire to secure by Letters Patent is:

The combination with a box, a lid on said 90 box and a flange on said lid extending over the top edges of said box, of a tie comprising two cords, each having its ends secured to the upper central portions of two adjoining sides of said box and portions extending over corresponding parts of said flange and said lid, each of said cords being of 95 100

a length so that its central portion will just pass over the upper corner between its corresponding sides of the box; a member between the central parts of said cords; and hooks on said member engaging said cords locking the latter in operative condition, substantially as described.

In testimony whereof we have signed our

names to this specification in the presence of two subscribing witnesses.

LUDWIG W. ZAAR.
JOSEPH UBELAKER.
